UNITED STATES PATENT OFFICE.

ARTHUR E. GAINES, OF DENVER, COLORADO.

ARTIFICIAL FOOT.

Application filed May 23, 1925. Serial No. 32,343.

This invention relates to improvements in artificial feet.

It is the object of this invention to produce an artificial foot that shall be of very simple construction, strong, light in weight, easily controlled and which eliminates stump jar and stump strain.

The above and other objects that will appear as the description proceeds are attained by means of a construction which I will now proceed to describe in detail, reference for this purpose being had to the accompanying drawing in which the preferred embodiment of my invention has been illustrated and in which:

Fig. 1 is a vertical longitudinal section through my improved foot;

Fig. 2 is a fragmentary bottom view looking in the direction of the arrow 2 in Fig. 1, a portion of the covering being removed so as to better show the construction;

Fig. 3 is a section taken on line 3—3, Fig. 1 and

Fig. 4 is a section taken on line 4—4, Fig. 1.

My improved foot is formed from two wooden portions 1 and 2 glued together and reenforced by means of the member 3. The toe portion of the foot is formed from a piece of felt 4, whose rear end 5 and the rear portion 6 of whose upper surface are cemented to the walls of a rectangular notch formed in the front end of the member 2. It will be noticed that the felt toe portion extends a considerable distance to the front of the front end 7 of member 2 and this permits the tip of the felt to bend, thereby giving a "toe movement" which corresponds to that of a natural foot. The rear end of member 2 has a cut out portion having a vertical wall 8 and a horizontal wall 9. Directly to the front of the vertical wall 8 is a notch 10 having a top 11, side walls 12 and 13 and vertical front end wall 14. The heel portion consists of a wooden member 15 provided at its front end with a tongue 16 which projects into the notch 10 in the manner quite clearly shown in Figs. 1 and 4. Member 15 is secured to member 2 by means of a specially constructed hinge which consists of a plate 17 that is wider than the notch 10 and which is fastened to member 2 by means of four screws 18. The front end of plate 17 is notched and the ends 19 are bent into circular loops for the reception of the hinge pin 20. A metal block 21 is se-

cured to the pin 20 between the ends 19 and has a threaded opening for the reception of the threaded end of the bolt 22 which is rotatably connected to the tongue 16 by means comprising a metal plate 23 that is provided with a longitudinal channel for the reception of the bolt 22 and the cover plate 24 which is held in place by rivets 25. It will now be apparent that the heel piece 15 can move up and down about the hinge pin 20 and that it can be rotated to a limited extent about the bolt 22. Both of these movements are of great importance in obtaining a natural operation. A felt pad 26 separates the plate 24 from the hinge member 17 (Fig. 1). Secured to the upper side of the member 15 is a rubber cushion 27 that engages the surface 9 when the heel piece 15 reaches its upper limit of movement. A similar rubber cushion 28 is secured to the underside of the heel piece 15 by means of cement and a dovetail connection comprising the transverse bar 29. A helical compression spring 30 that is enclosed in a leather casing 31 is located in a suitable opening in members 1 and 2 and has its lower end extending through the rubber cushion 27 and into engagement with the upper surface of the member 15. The parts are enclosed in a leather covering consisting of two pieces 32 and 33 that are sewed together along the bottom in the manner indicated by numeral 34 in Fig. 2. A stiff piece of leather 35 or other suitable material is attached along its upper edge to the member 2 and extends downwardly past member 15. This forms a guiding surface over which the movable heel member travels.

It will be seen from the above that my improved foot has several peculiarities of construction which are of great practical importance. In the first place the toe portion 4 extends forwardly beyond the foremost part of the rigid member 2 and is therefore adapted to bend, giving a natural toe action. The heel portion comprising members 15, 27 and 28 has an up and down movement about the hinge pin 20 and is acted upon by the spring 30, giving a comfortable cushion effect that prevents stump jar and stump strain. In case of sufficient force being applied to compress the spring 30, the rubber cushion 27 will prevent the jar that would take place if an unyielding surface were to come into contact with the surface 9. If the foot fails to engage the supporting sur-

face squarely; or if the surface is inclined to one side or another, the heel portion can twist about the bolt 22 thereby preventing undue strain on the stump. By the means described a full natural foot movement is obtained which permits the wearer to walk with practically no exertion and with comfort.

Having now described my invention, what I claim as new is:

- 10 1. An artificial foot comprising, in combination, a body member having portions corresponding with the ankle and fore part of a foot, said body member having a cut out portion for the reception of a heel member, a heel member located in said cut out, means for securing said heel member in place, said means permitting the heel to oscillate about transverse and longitudinal axes, the former of which is stationary with respect to both the ankle and toe portion of the body member and the latter of which may oscillate about the former and means comprising a spring and a stop for normally holding the heel in a predetermined position and for permitting it to yield upwardly when weight is applied thereto.
- 15 2. An artificial foot having an integral body member embodying the ankle and toe portions and a separate heel portion, means for attaching the heel portion to the body member in such a way that it may move about a transverse axis and about a longitudinal axis.
- 20 3. An artificial foot comprising, in combination, a body member having a cut away portion at the heel, a notch opening into said cut away portion, a heel member adapt-

ed to fit into said cut away portion, said member having a part that projects into said notch, means for securing said heel portion to the body member, said means comprising a hinge having two hinge pins one of which extends transversely of the foot and the other of which extends longitudinally of the foot and means comprising a spring for moving said heel portion about the transverse hinge pin.

4. An artificial foot comprising, in combination, a body member having a cut away portion at the heel, a notch opening into said cut away portion, a heel member adapted to fit into said cut away portion, said member having a part that projects into said notch, means for securing said heel portion to the body member, said means comprising a hinge having two hinge pins one of which extends transversely of the foot and the other of which extends longitudinally of the foot, means comprising a spring for moving said heel portion about the transverse hinge pin and means for guiding said heel portion as it moves about the transverse hinge pin.

5. An artificial foot comprising, in combination, a body portion, a heel portion pivotally attached thereto by means which permits it to move about two axes extending at right angles to each other, one of said axes extending transversely and the other longitudinally of the foot, means for limiting the movement about either one of the axes and means comprising a spring for exerting a force on the heel portion to move the same in one direction.

In testimony whereof I affix my signature.
ARTHUR E. GAINES.
